(57) **CLAIM**

The ornamental design for a tread portion of an automobile tire, as shown and described.

DESCRIPTION

FIG. 1 is a front view of a tread portion of an automobile tire; FIG. 2 is a perspective view thereof; FIG. 3 is a rear view thereof; FIG. 4 is a left side view thereof; FIG. 5 is a fragmentary enlarged view showing the details of the tread portion thereof; FIG. 6 is an end view taken along line 6-6 in FIG. 5; and, FIG. 7 is an end view taken along line 7-7 in FIG. 5. In the drawings, the broken lines defining the sidewall and the inner bead of the tire depict environmental subject matter that forms no part of the claimed design.
